UNITED STATES PATENT OFFICE.

EMIL SCHULZ, OF ALTDAMM, GERMANY.

SAFETY-CAGE FOR WATER-GAGES.

1,126,301.

Specification of Letters Patent. Patented Jan. 26, 1915.

Application filed August 15, 1913. Serial No. 784,934.

To all whom it may concern:

Be it known that I, EMIL SCHULZ, a subject of the King of Prussia, residing at No. 28 Stargarderstrasse, Altdamm, in the 5 Kingdom of Prussia, German Empire, have invented certain new and useful Improvements in Safety-Cages for Water-Gages, of which the following is a specification.

My invention relates to an improved 10 safety-cage for water-gages, destined to be employed in connection with steam-boilers of any kind, but particularly with marine-boilers. The means hitherto employed for preventing accidents occurring to the attendants of the boiler owing to the bursting of a water-gage do not afford sufficient security; they generally consist of a casing of strong glass or of a wire-netting surrounding the water-gage; but in the case 15 of the gage bursting suddenly under the high pressure of the steam, the glass casing will be broken in pieces and the wire-netting will be torn and the shivers of glass, mixed up with the pieces of wire and with hot 20 water and vapor will be hurled into the face and against the body of the attendant, a danger constantly menacing the members of the body and even the life of the engine-driver. The safety cages consisting of 25 wire-netting or the like, besides, are objectionable for the reason of greatly encumbering the ready and clear sight of the level 30 of the water in the gage-glass.

The object of my present invention is to 35 provide a safety cage which will offer perfect security to the attendants in the case of the gage glass bursting.

The safety cage of my invention consists 40 of an open, semi-circular frame surrounding the front part of the gage-glass and a kind of Venetian blind connected to the open front of said frame, the said blind being so constructed as to normally allow of ready inspection of the gage-glass to as- 45 certain at every moment the actual level of the water. As soon, however, as an inside pressure, such as will occur instantly when the gage-glass bursts, acts against the said blind, it will automatically shut up and pre- 50 vent the boiling water and shivers of glass from being hurled about, and the vapor escaping will also be prevented from issuing to the front in violent jets where it might injure the attendants. The said 55 safety-cage, furthermore, is so constructed as to prevent shivers of glass and hot water

from being hurled downward through the bottom portion of the cage, the said shivers, on the contrary, will be retained in the cage and the water escaping will run down 60 without doing any hurt.

To make my invention perfectly understood, I have illustrated the same in the accompanying drawings, in which:

Figure 1 represents a front-elevation of 65 the improved safety cage according to my invention; Fig. 2 is a side-elevation of the same; Fig. 3 is a similar side-elevation with the blind shown in the closed state; Fig. 4 is a sectional view of the safety-cage with 70 the blind opened, and Fig. 5 a sectional view with the blind shut up.

The safety cage consists of a strong frame 75 *a*, comprising two frame sides *a'*, *a''* connected at foot by a bottom piece *b*, and at top by a head-piece *i*.

A series of lugs *n* are formed on the front edge of each of the two frame-sides *a'*, *a''*, and through the said lugs or eyes project the pivot-pins *d*, and *e*, the bent rear ends of 80 said pins being, respectively, secured to the left and to the right side of semi-circular blind or shutter-slats *c*, acting, in their totality, in the same way as a Venetian blind. The pivot-pins *d*, *e*, of the said slats *c*, are 85 so located at or near the lower edge of the slats as to normally make the said slats turn with their upper edges toward the inside of the frame *a* or toward the gage glass, the said gage-glass *m* being indicated by 90 dotted lines in Fig. 1. The normal tendency of the said slats *c* to rest in this position retains them in the normally open or inclined position, as shown in Figs. 1 and 2, so that the gage-glass *m* is open to the view 95 of the attendant for ready inspection at any time. The pivot-pins *e* of the slats *c* (Figs. 1, 4 and 5) have their free ends bent to act as a brake and stop for preventing the slats *c* from being accidentally turned in to their 100 closed position as shown in Figs. 3 and 5, the said hook-shaped ends of the pivots *e* having a bearing contact against the frame side *a'*, and the points of said pivot pins resting in a slight groove *l* formed in the 105 frame side *a''*, the web *o*, serving as a stop to limit the inward motion of the said slats *c*.

It will be easily seen, that any pressure 110 working against the inside surface of the curved slats *c*, will at once cause said slats to turn on their pivot-pins *d*, *e*, and assume

the position shown in Figs. 3 and 5. The upper end of the topmost slat *c* will bear against the curved inside surface of the top-piece *i*, and the lower edge of each slat 5 slightly overlaps the upper edge of the next lower slat *c* of the series; each slat, then, will retain the next one below in its closed position, thus forming a continuous cover to the front-side of the frame *a*, which allows 10 of no shivers of glass, nor water, nor vapor from being thrown out from the bursting gage glass to the front of said cage.

Each of the frame-sides *a*, has a downwardly projecting arm *f'* formed or secured 15 at or near its lower end and a corresponding arm *f*, formed or secured to the top-piece *i*. The said arms *f* and *f'* are inserted through eyes in lugs *h* of the gage-glass carrier. A latch *g* is pivoted to the lower end of each 20 of said arms *f* and *f'*. When the said arms have been passed through their corresponding lugs *h*, the said latches *g* are turned into the horizontal position, as shown in the lower part of Fig. 2, and the frame or cage, thereby, is prevented from being accidentally thrown or disengaged from the gage-carrier.

If the gage-glass *m* should burst near its upper or its lower end, the fluid issuing from said gage-glass would not act upon the entire inside surface of the open slats *c*, and part of said slats would fail to shut up. To prevent such incomplete function of the safety-device, means have been provided to secure uniform and complete shutting-up 30 motion of the entire series of slats *c*, independent of the place where the actuating inside pressure happens to strike against the surface of one or several slats. To obtain such uniform motion, the said slats *c* are 35 connected to each other by a rod *r* pivoted to the outer ends of parallel arms *p*, the opposite ends of which are secured to the pivot pins *d* as shown in Fig. 4. Each slat *c*, accordingly, will transmit its forward, as 40 well as its rearward motion to the whole series of slats, and by this means the totality of the slats, forming a blind or shutter to the front of the frame *a*, will be forced to work together, thus causing the safety cage to 45 form a positive shield. The area offered to the inside pressure which may issue from the bursting gage-glass, being of considerable extent, and all of the slats always working in unison, the action of the device will be 50 reliable in any case. The series of slats being connected to each other to work to-

gether will also prevent any failure of one to act which might occur if the pivot-connection of one or the other slat should offer any resistance owing to rust, dust or any 60 obstacle.

The shape of the cage as well as the details of construction and combination of the sundry parts of the device might of course be varied according to the requirements, 65 without departing from the leading features of the invention, as indicated by the claims.

I claim as my invention:

1. In a safety cage for water-gages, the combination with the gage-glass carrier, of a frame and a blind covering the open front of said frame, said blind being composed of a plurality of slats overlapping each other and so pivoted to the frame sides as to be automatically closed by a sudden increase 70 of pressure on the inner side of the blind, and means whereby they are connected to each other to simultaneously open and close, substantially as and for the purpose set forth.

2. In a safety-cage for water-gages, the combination with the gage-glass carrier, of a frame comprising lateral frame sides, a bottom piece, a top-piece connecting the upper ends of the frame sides, a blind comprising a plurality of slats covering the open front of said frame and so pivoted to the frame sides, as to be automatically closed by a sudden increase of pressure on the inner side of the frame, and means for connecting the plurality of slats for simultaneous operation, substantially as and for the purpose set forth.

3. In a safety-cage for water-gages, the combination of a frame comprising lateral frame sides, a bottom piece and a top-piece connecting said frame sides, slats pivoted to said frame sides, arms to which the pivot-pins at one of the ends of said slats are rigidly connected, means whereby said arms are connected to each other to make the plurality of slats work in unison, and the pivot pins at the other ends of said slats being formed to act as a brake bearing against the lateral frame side, substantially as and for the purpose set forth.

In testimony whereof I affix my signature in presence of two witnesses.

EMIL SCHULZ.
